Primary Examiner — Rhea Shields(74) *Attorney, Agent, or Firm* — Todd R. Miller(57) **CLAIM**

The ornamental design for a flip top container, as shown and described.

DESCRIPTION

FIG. 1 is a top perspective view of the flip top container, in a closed configuration;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a top perspective view of the flip top container, in an open configuration.

In the drawings, the broken lines are for the purpose of illustrating portions of the flip top container that form no part of the claimed design.

1 Claim, 6 Drawing Sheets(56)
